UNITED STATES PATENT OFFICE.

MORRIS MOSKOWITZ, OF NEWARK, NEW JERSEY, ASSIGNOR TO THE NATIONAL ELECTRIC CAR LIGHTING COMPANY, OF WEST VIRGINIA.

MAKE-AND-BREAK SWITCH.

SPECIFICATION forming part of Letters Patent No. 542,772, dated July 16, 1895.

Application filed April 23, 1895. Serial No. 546,822. (No model.)

To all whom it may concern:

Be it known that I, MORRIS MOSKOWITZ, a citizen of the United States, residing at Newark, in the county of Essex and State of New Jersey, have invented certain new and useful Improvements in Make-and-Break Switches; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

15 My present invention relates to a novel form of make-and-break switch for electrical purposes, which shall be of a simple construction, and which is sensitive and efficient in its operation.

20 The object of this invention, therefore, is to provide a novel form of switch, which is sensitive, delicate, and very efficient in its operation, and in which the use of the ordinary mercury-cups, now employed in delicate switches 25 of this class, is entirely dispensed with, and in which the mechanical action to operate the switch is derived directly from an electromagnetic pull. Heretofore electromagnetic switches of this class were operated by dipping a piece of copper wire into mercury-cups 30 in order to establish or complete the electrical circuit to enable any delicate magnet to perform its work, as it is well known that the mercury offers but very little resistance to the entrance of the copper wires into the mercury-bath.

35 These forms of contacts for switches, however, are objectionable, in that the mercury is being constantly burned away and the copper is oxidized, so that it becomes a poor 40 conductor. Other constructions, such as the ordinary hand-switch, have been devised, but this construction requires a powerful electromagnet to operate the same, and which would have to be so large as to make a failure of the 45 construction from a practical and commercial standpoint.

In my present construction of switch I use a small commutator and brushes, much of the same construction employed in small electric 50 motors, with the brushes adjusted so that two opposite brushes will rest against two oppositely-placed commutator-sections which are

electrically connected and establish a complete circuit for the flow of the current when the commutator has been partially rotated by 55 the action of a shunt-magnet and its armature bar mechanically connected with the commutator.

The invention, therefore, consists in the novel construction of make-and-break switch, 60 and also in the details of construction and arrangements and combinations of parts, such as will be hereinafter fully described, and finally pointed out in the clauses of the claim.

Referring to the accompanying drawings, 65 in which similar letters of reference are employed in each of the several figures to indicate like parts, Figure 1 is a face view of my novel form of make-and-break switch, illustrating the parts thereof in their normally inoperative positions, and Fig. 2 is a top view 70 of the same. Fig. 3 is a view similar to that illustrated in Fig. 1, with the parts in their operated positions when contact is made. Fig. 4 is a cross-section of the commutator, illustrating one manner of electrically connecting 75 the opposite commutator-sections, and Fig. 5 is a similar view illustrating a different manner of connecting the commutator-sections. Fig. 6 is a side view of the switch when the 80 several parts are in their normal positions indicated in Fig. 1. Fig. 7 is a like view of the switch with the parts in the positions illustrated in said Fig. 3, and Fig. 8 is a detail view of a sensitive spring-contact used in connection with the apparatus. 85

In said drawings, A is a suitable board or base to which is secured my novel form of make-and-break switch. The same comprises therein a suitable high-resistance or shunt 90 magnet a and a series magnet a' , having the usual forms of magnetic cores a^2 and a^3 , respectively, and are connected by the cross plates or pieces a^4 and a^5 at the top and bottom and a rod or post a^6 , substantially as 95 shown in Figs. 1 and 3. Journalled to a post or standard b on said base A is the armature b' , provided with the contacts b^2 and b^3 , respectively, which are adapted to establish 100 electrical contact with the ends of the cores a^2 and a^3 , as will be clearly evident. On the free end of said bar or armature b' is an arm b^4 having a spring b^5 , which is normally in electrical contact with a suitable pin or spring

contact b^6 , as will be seen from an inspection of Figs. 1 and 6. Pivotaly connected with the free end of said armature-bar b' , by means of a screw or pin c' , but insulated therefrom, as shown, is a connecting link or rod c , which is operatively and pivotally secured at its opposite end, by means of a pin or screw c^2 , to a small commutator d , which it partially rotates when the armature-bar b' is attracted by the electro magnet or magnets, as will be more fully set forth hereinafter. Said commutator d , as will be seen from Figs. 4 and 5, comprises therein certain commutator sections d' and d^2 , which are insulated from each other by any suitable insulating material d^3 , substantially as shown, said sections d^2 being electrically connected by a suitable connection d^4 , as in Figs. 4 and 5, or in any other suitable manner, while the sections d' are open-circuited, or in other words, there is no electrical connection between them. Said sections or segments d' and d^2 are suitably secured between the end plates d^5 and d^6 , having a pivotal support d^7 , which is arranged in the bearing-bar d^8 of the frame d^9 and in a suitable bearing in the base A, as will be understood from an inspection of Figs. 6 and 7. In sliding contact with the outer surfaces of said sections d' and d^2 are suitable brushes e arranged on spring-arms e' , which are securely arranged on the ends of suitable posts or standards e^2 on said base A. Only two of such contact-brushes e are necessary to produce an operative make-and-break switch; but I may use four, or six, or more, the purpose of which will be more fully described hereinafter.

As shown in Figs. 1 and 3, the armature-bar b' is connected with the usual form of tension-spring f and the adjusting-screws f' and f^2 . The contact b^2 on the bar b' is also adjustably arranged thereon by being secured to an adjusting-screw b^7 and the nut b^8 on said screw. On the top of the said armature-bar b' I have also secured a small shunt-magnet g , the end g' of which is normally brought against two spring-arms h and h' , secured to the base A by screws h^2 , each arm being provided with slightly-projecting contacts h^3 , which are forced against the contacts h^4 on the spring-arms h^5 and h^6 , secured to the base A by means of the screws h^7 , as will be clearly seen from Figs. 1, 3, and 8. Said arms h and h' and h^5 and h^6 are suitably connected by a resistance coil i and wires (not shown in the present case) connecting the same with the commutator d for the purpose of overcoming any possibility of sparking when the brushes e pass from the sections d' to the sections d^2 or from the sections d^2 to the sections d' .

I will now describe the operation of the parts comprising my novel form of make-and-break switch. It is briefly as follows:

I have illustrated my novel form of switch in connection with a secondary battery k , and it is designed to make or complete the circuit when the electro motive force of the dynamo

exceeds that of the battery and to break the circuit when the electromotive force from the dynamo falls below that of the battery. The operation of thus making and breaking the battery-circuit will be understood from the following description:

The current flows in the direction of the arrows, coming in at the binding-post x , and follows the circuit 11 to the pin or spring-contact b^6 , thence by the spring b^5 and arm b^4 through the armature-bar b' , wire 2, into the magnetic-coil forming the shunt-magnet a , and out by the circuit-wires 3 4 to the binding-post x^2 to the source of electrical energy. The shunt-magnet a immediately energizes the core a^2 and causes the contact b^2 on the bar b' to make electrical contact with said magnetic core a^2 . The operation of the link 85 c in partly rotating the commutator d causes a closed circuit through the commutator-sections, at the same time breaking the contact between the pin b^6 and the spring-contact b^5 , as shown in Figs. 3 and 7, and the main circuit between the main source of electricity and a battery k or other electrical appliances in the circuit 5 5, connected with the binding-posts x^2 and x^3 and with the binding-posts x' , is then closed through the series magnet a' . The current now flows in the direction of the arrows through the circuit-wires 1 6 to one of the brush-arms e' and its brush, through the electrically-connected commutator-sections d^2 , to the opposite brush e and its arm e' , into the circuit-wire 7 to the coil on the series magnet a' . The current then passes through said coil and out into the circuit-wire 8 into the binding-post x^3 , thence through the circuit 5 5 into the battery k , and finally to the binding-posts x^2 , from which it passes to the post x' and out, back to the original source of electricity. Thus it will be seen that while the shunt-magnet a has now been cut out of circuit, the contact b^2 on the armature-bar b' is held by the magnetic core a^2 in the series magnet a' and the circuit is still complete. The series magnet a' being of insufficient strength to attract the armature-bar b' in the first place, being controlled by ampères instead of volts, as is the case with the shunt-magnet a , it will be seen that said shunt-magnet must be cut out of circuit; otherwise it will still hold on to the armature-bar b' , when the voltage of the dynamo in the main circuit equals that of the battery. When this happens it becomes necessary that the make-and-break switch should be open, which it could not do and would not do if the shunt-magnet a were still in an unbroken circuit, but which it will do with the series magnet in circuit. As soon as the connection is again broken between the series magnet and the bar b' , all the parts return from their operated positions, illustrated in Fig. 3, to their normally inoperative positions, (illustrated in Fig. 1,) and contact is again established between the spring pin b^6 and the spring b^5 , connected with the bar b' , as will be clearly understood.

As shown in Fig. 1, the small shunt-magnet *g* on the armature-bar *b'* is in a shunt-circuit connected with the binding-posts *x* and *x'* and is intended as a safeguard.

If through any cause whatever the tension-spring *f* should not act to withdraw the bar *b'* from its contact with the series magnet *a'*, and there should be a reaction of current from the battery to the dynamo in the main circuit, then the current would become reversed in the series magnet, changing the polarity of its magnetic core *a*³, and the result would prove a serious one. To avoid this the small shunt-magnet *g* has been used. This magnet being in a shunt-circuit the current through the magnet cannot be reversed, and hence its polarity will not become changed. Should the polarity in the series magnet *a'* become changed the result will be that the polarity of the contact *b*³, which is part of the magnetic core of the electromagnet *g*, will be the same as the polarity of the upper portion of the core *a*³ in the series magnet *a'*, and the result will be that these like poles will immediately repel each other. This will cause the armature *b'* to be held away from the series magnet *a'* until again attracted by the current controlling the action of the shunt-magnet *a*.

My novel form of make-and-break switch is especially adapted in systems for lighting trains by electricity generated from a dynamo on a car-wheel axle, in which the dynamo armature is subject to reversal of rotation and varying speed; but the operation of the apparatus need not be further described here in connection with the dynamo when used in this manner, it being my intention and purpose to use the apparatus in any system of electrical wiring and appliances arranged therein to which it is applicable.

It is obvious that the precise form and arrangements of the parts herein shown are not essential to the present invention, and they may be varied without departing from the scope of my present invention. Hence I do not limit myself to the exact arrangements and combinations of the parts herein shown, claiming, broadly, the arrangement of an electromagnet and armature-bar operating a commutator to establish a complete circuit through a working-circuit to produce a sensitive and very delicate construction of make-and-break switch.

As has been previously stated, I may use more than two brushes *e* and arms *e'* in connection with the commutator *d*, as will be clearly seen from Fig. 1, which can be arranged in other circuits, as 10, 11, &c., and in which are arranged electrical translating devices to be controlled by the action of the make-and-break switch.

Having thus described my invention, what I claim is—

1. In a make and break switch, an electro-magnet in shunt circuit and an electro-magnet in series, and a commutator controlled by said shunt magnet to establish a complete circuit through said series magnet and cut said shunt magnet out of circuit, said commutator comprising therein, commutator sections *d'* which are open-circuited, and commutator sections *d*² which are electrically connected, substantially as and for the purposes set forth. 75

2. In a make and break switch, an electro-magnet in shunt circuit, an electro-magnet in series, a combined armature bar, a commutator, and a link connection between said armature bar and commutator to establish a complete circuit through said series magnet and cut said shunt magnet out of circuit, substantially as and for the purposes set forth. 80

3. In a make and break switch, an electro-magnet in shunt circuit, an electro-magnet in series, a combined armature bar, a commutator, and a link connection between said armature bar and commutator to establish a complete circuit through said series magnet and cut said shunt magnet out of circuit, said commutator comprising therein, commutator sections *d'* which are open-circuited, and commutator sections *d*² which are electrically connected, substantially as and for the purposes set forth. 85

4. In a make and break switch, an electro-magnet in shunt circuit, an electro-magnet in series, a combined armature bar, a commutator, and means connecting said commutator with said armature bar to establish a complete circuit through said series magnet and cut said shunt magnet out of circuit, and a shunt magnet *g* on said armature bar in a shunt circuit, substantially as and for the purposes set forth. 90 95

5. In a make and break switch, an electro-magnet in shunt circuit, an electro-magnet in series, a combined armature bar, a commutator, and means connecting said commutator with said armature bar to establish a complete circuit through said series magnet and cut said shunt magnet out of circuit, a shunt magnet *g* on said armature bar in shunt circuit, spring contacts *h*—*h'* and *h*²—*h*³, and a resistance coil, all arranged, substantially as and for the purposes set forth. 100 105 110 115

In testimony that I claim the invention set forth above I have hereunto set my hand this 18th day of April, 1895.

MORRIS MOSKOWITZ.
